CARRIAGE RETURNING AND PAPER FEEDING APPLIANCE FOR TYPEWRITERS

Eugène Trullemans, Lausanne, Switzerland

Application February 14, 1950, Serial No. 144,164
In Switzerland February 25, 1949

9 Claims. (Cl. 197—66)

1

This invention relates to an appliance designed for the return of the carriage of a typewriter and for the forward feeding of the paper, and comprises an electric motor driving a drum upon which is wound a cable secured to the carriage.

This appliance is characterized by a clutch or coupling arranged between the motor and the carriage and designed to transmit a predetermined maximum torque, this coupling comprising two parts which are movable relatively to one another and which are displaced when the torque exceeds the said maximum, thus producing the disengagement of the coupling, these parts being connected with an electric switch controlling the motor, all in such a way that the excess pull on the cable due to the arrival of the carriage against a stop at the end of its stroke produces the disengagement of the coupling and the stoppage of the motor.

One form of construction of the invention is illustrated by way of example in the accompanying drawings, in which:

Figure 1 is a diagrammatic plan view of a typewriter equipped with the present appliance;

Figure 2 is a profile view on a larger scale of a detail of Figure 1;

Figure 3 is a horizontal section of the appliance, the plane of section passing through the drum on which the cable is wound;

Figure 4 shows a detail in sectional elevation on the line IV—IV in Figure 3;

Figure 5 is a view of one of the walls of the frame of the appliance and of the parts that are fixed thereto;

Figure 6 shows a section of a detail on the line VI—VI in Figure 3;

Figure 7 is a section on the line VII—VII in Figure 6; and

Figures 8 and 9 are views in section, corresponding to Figures 6 and 7 respectively, showing a modification.

The writing machine illustrated in Figure 1 is denoted by 1, and its carriage by 2. The appliance designed for returning the carriage is denoted by 3. It is detachably fixed to the frame of the machine by a flange, not shown. This appliance comprises a motor 4, actuating a drum 5 (Figure 3), upon which is wound a cable 6. This cable may be of metal, nylon, or any other strong and flexible material. This cable is connected to the line-spacing lever 11 of the machine, either directly or through the medium of an additional device, according to the type of machine upon which the appliance is mounted. Here the cable is hooked on to a hook 7a, pro-

vided on a lever 7 (Figure 2), pivoted at 8, and controlling, by means of a peg 9, an arm 10 fixed to the line-spacing lever 11. This arrangement enables the return of the carriage and the changing of the line, that is to say, the forward feeding of the paper, to be effected simultaneously.

In Figure 3, the end of the shaft 12 of the motor is visible. This shaft, by means of a screw-driver coupling 13, drives a shaft 14 carrying a worm, not represented, co-operating with a wheel 15 keyed on to a sleeve 16, which turns in bearings 17 carried by a part 18a of the frame 18 of the apparatus. The sleeve 16 carries a wheel 19 provided with a spur 20 designed to co-operate with spurs 21 on a coupling disc 22. This disc is rigid with a barrel 22a sliding upon a shaft 23. The latter is likewise slidingly mounted upon two trunnion rods 24 fixed to the frame 18. A helical spring 25 bearing against a stop 26 fixed to the shaft 23 tends to press the disc 22 against a second coupling disc denoted by 27. The disc 22 is provided with three dogs 28 spaced apart at angles of 120 degrees, and designed to enter corresponding cavities 29 in the disc 27. These dogs 28 and these cavities 29 have contact surfaces 30 at an inclination to the axis of rotation, as shown in Figure 7. The disc 27 is rigid with a sleeve 31, upon which the drum 5 is rotatably mounted, and to which is fixed a small plate 32. This plate carries a peg 33, to which is fixed the end of a spiral spring 34, the other end of which is fixed to a flange 5a of the drum 5. The disc 27 therefore drives the drum 5 resiliently through the medium of the spring 34. A screw 35 in the drum 5 extends into an arcuate slot 36 in the disc 27 and thus limits the relative displacement between the disc 27 and the drum 5. The sleeve 31 carrying the drum 5, and also the discs 22 and 27, are axially movable with the shaft 23.

One wall of the frame, denoted by 18b, is represented in Figure 5. This wall carries a rocking lever 37 pivoted upon a pin 38, with which it is rigid. The pin 38 is perpendicular to the axis of rotation of the drum. The lever 37 carries two pegs 39 and 40, situated one on each side of the drum 5 and of the disc 27. The oscillations of the lever 37 thus produce axial displacements of the drum 5 and of the disc 27, while conversely these axial displacements produce oscillations of the lever. A jumper 41 pressed against the lever 37 by a spring 42 establishes two stable positions of the lever. The lever 37 has a lug 37a actuating an oscillating cam 43, which closes an electrical contact 44 supplying current to the

motor. This contact is carried by a resilient blade 45, which tends to occupy a position in which the circuit is open.

The appliance furthermore comprises a control rod 46 (Figure 1), co-axial with the pivot 38 and angularly rigid with this pivot. This rod is rotatably mounted upon a bracket 47 fixed to the frame of the machine. A control lever 48 is fixed to the rod 46.

The appliance operates in the following manner: The various parts being in the positions illustrated in the drawings, a pressure exerted upon the lever 48 produces a rotation of the lever 37 in the direction denoted by the arrow 49, which on the one hand produces the closure of the contact 44 and the starting of the motor 4, and on the other hand the displacement, by means of the peg 39, of the drum 5 and of the shaft 23 with all that it carries. The spurs 21 then enter the path of the spur 20, and the disc 22 is rotated. The dogs 28 drive the disc 27, which is rigid with the sleeve 31. The drum 5 is then driven through the medium of the spring 34, and the cable 6 winds on to the drum. The latter may be provided with a helical groove ensuring the regular winding of the cable. The carriage is then displaced by the cable in the direction of the arrow 50 in Figure 1. When it reaches the end of its travel it strikes against a stop, and the tension of the cable suddenly increases. Due to the obliquity of the contact surfaces 30 between the dogs 28 and their cavities 29, the increase in the torque to be transmitted produces the displacement of the disc 27 in the direction of the arrow 66. The dogs 28 come out of the cavities 29, and the disc 27, as well as the drum 5, are no longer actuated. At the same time the displacement of the disc and of the drum produces the opening of the contact 44 and the stoppage of the motor. By its inertia the motor continues to turn, and as soon as the dogs 28 come opposite to the cavities 29 they enter these cavities under the action of the spring 25, and the various parts of the appliance again occupy the positions illustrated in the drawings. The spur 21 being no longer located in the path of the spur 20, it is possible to manipulate the carriage by hand without rotating the motor.

A device is provided which keeps the cable 6 taut. This device, shown in Figure 4, comprises a barrel of which the hub, denoted by 51, is fixed to the part 18a of the frame 18, and of which the cage, denoted by 52, carries a gear wheel 53, meshing with a pinion 54 carried by the shaft 23. A spiral spring 55 is fixed at one end to the hub 51 and at the other end to the cage 52. This spiral spring stretches to a greater or less extent according to the position occupied by the carriage, and keeps the cable 6 taut.

Figures 8 and 9 illustrate a modification of the coupling device. In this modification the disc carrying the dogs is denoted by 56, and the disc provided with the cavities by 57. The cavities are denoted by 58, and the dogs by 60. The contact surfaces between the dogs and the cavities, denoted by 61, are parallel to the axis of rotation. The disc 56 is furthermore provided with nipples 62, which enter the cavities 58, and are each provided with a surface 63 at an inclination to the axis of rotation. Pegs 64, rigid with the drum 5 and parallel to the axis, enter the cavities 58. When the torque to be transmitted exceeds a certain value, a relative displacement is produced between the drum

5 and the disc 57 against the resistance of the spiral spring 34. In relation to the disc 57, the pegs 64 are displaced in the direction of the arrow 65. Then they come into contact with the surfaces 63, they push the nipples 62 out of the cavities, producing a relative axial displacement of the two discs, so that the dogs 60 come out of the cavities 58, and disengagement takes place.

The invention is of course not limited to the embodiment here described. Several types of couplings could especially be used, such as gear-couplings, friction-couplings or electro-magnetic couplings.

What I claim is:

1. An appliance for returning the carriage of a typewriter and feeding the paper forward, detachably mounted upon the frame of the typewriter, comprising a cable attached to the carriage, a drum upon which is wound said cable, an electric motor for driving said drum, a coupling interposed between said motor and said drum and designed to transmit a predetermined maximum torque, this coupling comprising two members movable relatively to one another and arranged in such a manner that one is displaceable relatively to the other to produce the disengagement of the coupling when the torque exceeds the said maximum, and an electrical switch controlling the motor, said switch being connected with the displaceable one of said members, whereby the excess pull on the cable due to the arrival of the carriage against an end-of-travel stop produces the disengagement of the coupling and the stoppage of the motor.

2. An appliance for simultaneously returning the carriage of a typewriter and feeding the paper forward, detachably mounted upon the frame of the typewriter, comprising a cable attached to the line spacing control lever of the typewriter, a drum upon which is wound said cable, an electric motor for driving said drum, a coupling interposed between said motor and said drum and designed to transmit a predetermined maximum torque, this coupling comprising two members movable relatively to one another and arranged in such a manner that one is displaceable relatively to the other to produce the disengagement of the coupling when the torque exceeds the said maximum, and an electrical switch controlling the motor, said switch being connected with the displaceable one of said members, whereby the excess pull on the cable due to the arrival of the carriage against an end-of-travel stop produces the disengagement of the coupling and the stoppage of the motor.

3. An appliance for returning the carriage of a typewriter and feeding the paper forward, comprising a cable attached to the carriage, a drum upon which is wound said cable, an electric motor for driving said drum, a coupling interposed between said motor and said drum and designed to transmit a predetermined maximum torque, this coupling comprising two discs, a spring tending to press said discs one against the other, one of these two discs being provided with at least one dog and the other with at least one cavity, said dog being designed to enter said cavity under the action of said spring and to leave said cavity when the torque exceeds the said maximum, thus producing the disengagement of the coupling, and an electrical switch controlling the motor, said switch being connected with one of said discs, whereby the excess pull on the cable due to the arrival of the carriage against an end-of-

travel stop produces the disengagement of the coupling and the stoppage of the motor.

4. An appliance as claimed in claim 3 in which said dog is equipped with a plane which is inclined to the axis of rotation and in which the cavity is equipped with a corresponding plane designed to cooperate with the inclined plane of the dog in such a way that when the torque exceeds the said maximum the pressure of these two inclined planes against one another will produce a relative axial displacement of the two discs, thus bringing the dog out of the cavity, and thereby disengaging the clutch.

5. An appliance for returning the carriage of a typewriter and feeding the paper forward, comprising a cable attached to the carriage, a drum upon which is wound said cable, an electric motor for driving said drum, a coupling interposed between said motor and said drum and designed to transmit a predetermined maximum torque, this coupling comprising two discs coaxial with said drum, a spring tending to press said discs one against the other, one of these two discs being provided with at least one dog and the other with at least one cavity, said dog being designed to enter said cavity under the action of said spring and to leave said cavity when the torque exceeds the said maximum, thus producing the disengagement of the coupling, a spiral spring connecting one of said discs with said drum in such a way that this disc resiliently drives the drum and that the impact of the carriage against an end-of-travel stop is absorbed, and an electrical switch controlling the motor, said switch being connected with one of said discs, whereby the excess pull on the cable due to the arrival of the carriage against the end-of-travel stop produces the disengagement of the coupling and the stoppage of the motor.

6. An appliance as claimed in claim 5, in which the second of the two discs is provided with means for coupling with a member constantly driven by the motor, in such a way that this disc is coupled to or uncoupled from the said member according to the axial position that it occupies.

7. An appliance as claimed in claim 5, in which the drum is actuated by the disc provided with the cavity, the planes of contact between the dog and the cavity are parallel to the axis of rotation, and the drum is rigid with a peg parallel to the said axis, this peg entering the cavity in order to co-operate by means of its end with a plane which is inclined to the axis of rotation

presented by the disc, in such a way that when the torque exceeds the said maximum a relative angular displacement of the drum and disc is produced, which actuates it against the resistance of the spiral spring, that this relative displacement produces the displacement of the two discs by the co-operation of the peg and the inclined plane, and that the dog is pushed out of the cavity, which produces the disengagement of the clutch.

8. An appliance for returning the carriage of a typewriter and feeding the paper forward, comprising a cable attached to the carriage, a drum upon which is wound said cable, an electric motor for driving said drum, a coupling interposed between said motor and said drum and designed to transmit a predetermined maximum torque, this coupling comprising two discs, a spring tending to press said discs one against the other, one of these two discs being provided with at least one dog and the other with at least one cavity, said dog being designed to enter said cavity under the action of said spring and to leave said cavity when the torque exceeds the said maximum, thus producing the disengagement of the coupling, an electrical switch controlling the motor, said switch being connected with one of said discs, whereby the excess pull on the cable due to the arrival of the carriage against an end-of-travel stop produces the disengagement of the coupling and the stoppage of the motor, a rocking lever pivoted upon the frame of the appliance and of which the axis of oscillation is perpendicular to the axis of rotation of the coupling, said electrical switch being controlled by said lever, and two nipples carried by said rocking lever and situated one on each side of one of the two discs, in such a way that this lever oscillates, when axial displacements of said discs occur.

9. In an appliance as claimed in claim 8, a manipulating member which enables the rocking lever to be actuated manually.

EUGÈNE TRULLEMANS.
